RECORDING SYSTEM FOR TELEPHONES

Kenneth R. Hyman, Houston, Tex., assignor to
R. E. Willson, San Antonio, Tex.

Application March 28, 1938, Serial No. 198,475

32 Claims. (Cl. 179—5.5)

This invention relates to new and useful improvements in recording systems for telephones.

It is well known that every telephone subscriber is, at some time or another, absent from his home or place of business, when a telephone call or calls comes through to his station and, as a result, the subscriber misses the call, or calls, and has no way of knowing that another subscriber has attempted to reach him. Particularly, in the case of doctors, or other professional men, where the incoming call may be important, is this disadvantageous for it may be several hours before the calling subscriber may again put through his call.

It is, therefore, one of the objects of this invention to visibly record or register the number of the calling station at the called station, so that in the event that the called subscriber is absent when the call is put through, said called subscriber, upon his return, is advised of the station of the person who has attempted to reach him during his absence.

An important object of the invention is to provide an improved recording system for setting up the number of the calling station, at the called station, wherein the central office telephone equipment is utilized to transmit electrical impulses which represent the calling station's telephone number, whereby the recording system may be applied to any usual telephone system without a material change in the latter.

Another object of the invention is to provide an improved system which includes a sending or transmitting unit which is associated with the calling station, being preferably located at the exchange, and a receiving unit located at the called station, both units being electrically connected through the central telephone office equipment when the call between stations is completed through such equipment; the transmitting unit having means for transmitting electrical impulses which represent the number of the calling station, while the receiving unit is provided with means for transposing the impulses into visible registrations at the called station, whereby the telephone number of the calling station is set up at the called station.

A further object of the invention is to provide an improved recording system, of the character described, wherein the transmitting unit is operated when the call is complete and the connection between the calling and called stations is made, whereby the impulses are transmitted during the ringing period; the receiving unit transposing said impulses into visible indications im-

mediately upon receipt thereof, which is during the ringing period, said receiving unit being so constructed that said visible indications remain until such time as the called subscriber subsequently uses his telephone instrument, at which time the receiving unit is cleared.

Still another object of the invention is to provide an improved recording system including a receiving unit having a plurality of visible registers or recording devices, whereby a plurality of calls made during the absence of the called subscriber may be visibly registered or recorded in their proper order; there being means for clearing said registers when the called subscriber subsequently uses his telephone instrument, whereby said registers are made ready to receive further calls.

An important object of the invention is to provide an improved telephone recording system which is operable on either manual or automatic (machine switching) telephone systems and which is readily adaptable to the rotary and panel systems now in general use.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an elevation of the transmitting unit mechanism, constructed in accordance with the invention, and having the cover of its casing removed so as to show the interior thereof, 35

Figure 2 is a horizontal, cross-sectional view taken on the line 2—2 of Figure 1,

Figure 3 is a partial transverse, vertical, sectional view taken on the line 3—3 of Figure 2,

Figure 4 is an isometric view of the commutator wheel which has portions thereof broken away to more clearly illustrate the same,

Figure 5 is a wiring diagram of the transmitting unit,

Figure 6 is a complete wiring diagram of the transmitting unit and receiving unit, showing the hook-up of these units with the usual telephone equipment of the main office,

Figure 7 is a transverse, vertical, sectional view taken through the receiving unit housing,

Figure 8 is a horizontal, cross-sectional view taken on the line 8—8 of Figure 7,

Figure 9 is an isometric view of one of the indicator disks and its associate parts,

55

Figure 10 is a horizontal, cross-sectional view taken on the line 10-10 of Figure 7, and

Figure 11 is a wiring diagram of the receiving unit.

5 The recording system shown in the drawings includes a transmitting or sending unit which is connected to each station's incoming line at the central office of the telephone company. This unit, as will be explained, sends the telephone 10 number of its station through the central office equipment to the called station and this number is transmitted in the form of interrupted impulses of positive and negative electrical potential. The 15 electrical impulses are of a high frequency current and are superimposed upon the ringing current flowing to the called station. A receiving unit is located at the called station to receive the impulses and transpose them into visible indications or numerals which correspond to the 20 number of the calling station. The indications or numerals may be set up by a mechanical register which is located at the called station. The transmitting and receiving units are actuated immediately upon the completion of the connection, 25 through the central office, between the calling and called stations and are automatically operated without assistance from either the calling or called party. The recording or registration is completed during the first ringing period at the called station and remains set up and visible until the receiver of the telephone instrument at the called 30 station is lifted and replaced, at which time the register, or other indicating mechanism is cleared. In the event that the called party lifts his receiver 35 before the first ringing period is complete, the receiving unit is constructed so as to complete the registration.

With such arrangement, a visible recording, 40 setting forth the number of the telephone station which is calling, is set up at the called station. If the called subscriber is absent, then upon his return he can note the recording and thus be advised of the numbers of the telephone stations which have attempted to reach him. 45 Provision is also made in the system, as will be hereinafter explained, for the recording of several numbers, in the event that several stations call a particular station during the absence of the subscriber of that called station.

50 *The transmitting unit*

Referring to Figure 1, wherein the transmitting unit T is shown, the numeral 10 designates a casing or housing, which has a general rectangular shape. One side of the casing is open and this 55 open side is closed by a removable cover 11, both casing and cover being preferably constructed of insulating material. This casing is mounted upon a suitable frame (not shown) in the exchange and is electrically connected, as will be explained, 60 with the calling station.

A commutating code wheel 12, which is constructed of vulcanized fibre, moulded Bakelite, or other insulating material, is mounted within the casing, being located at one side of the upper end thereof. The code wheel is journaled on a 65 stub shaft 13 which is secured in the wall of the casing and, as is clearly shown in Figure 2, the shaft extends transversely within the casing. A plurality of metallic commutating bars or contacts 14 are embedded in the commutating wheel and these contacts are electrically interconnected with each other. The bars or contacts are located adjacent the periphery of the code wheel and are 70 arranged to represent the telephone number of

the station with which the code wheel is associated. Referring to Figure 5, the contacts are arranged as shown, and said contacts are connected to a source of high frequency electromotive force, which is illustrated as a generator or 5 impulsive machine 15. The negative side of the generator is connected by a wire 15a to a plurality of contacts 14a which are located on one side of the code wheel. These contacts represent the first numeral of the telephone number. It is 10 noted that four contacts are shown. The positive side of the generator is connected by a wire 15b with a segment 14b, which segment is located on the code wheel exactly opposite the contacts 14a, whereby the segment 14b occupies the same 15 radial position as the contacts, except that it is on the opposite side of the code wheel. The current is carried from the wires 15a and 15b to the contacts and segments on the rotatable code wheel by brushes 15e which ride on the periphery 20 of said wheel.

The contacts 14a are connected by a wire 16 with a second series of contacts 16a, which are located adjacent the segment 14b and on the same side of the code wheel. This places the 25 contacts 16a on the opposite side of the code wheel, with relation to the contacts 14a, and said contacts 16a represent the second numeral of the telephone number. Directly opposite the contacts 16a and adjacent the contacts 14a, is a 30 segment 16b which is connected to the segment 14b by a wire 16'. The segment 16b occupies the same radial space as the contacts 16a and is on the opposite side of the code wheel. A wire 17 connects the contacts 16a with a third series 35 of contacts, which series is shown as comprising one contact 17a representing the third numeral of the telephone number. This contact is, of course, located on the same side of the code wheel as are the contacts 14a and segment 16b. Directly opposite the contact and occupying substantially the same radial space on the other side of the code wheel, is a segment 17b which has connection through a wire 17' with the segment 16b. Contacts 18a are embedded in the wheel 45 adjacent the segment 17b, being connected by a wire 18 to the contact 17a which is disposed on the opposite side of the code wheel, and the contacts 18a represent the fourth numeral of the telephone number. A segment 18b, having electrical connection with the segment 17b through a wire 18', is located directly opposite the contacts 18a and occupies the same radial space on the other side of the code wheel. The contacts 18a are connected to the wire 15a, through one of the 55 brushes 15e, while the segment 18b is connected to the wire 15b, through the other brush 15e, whereby the positive side of the generator is connected to the segments, while the negative side has connection with the contacts. The contacts and segments on each side of the code wheel are in the same radial path and manifestly, the contacts and segments are alternately spaced. The number of series of contacts and the number of contacts in each series are subject to variation, 65 being dependent upon the telephone number of the station associated with the code wheel.

A pair of spring contact brushes or wipers 19 and 20 are disposed one on each side of the code wheel (Figure 2) and have their outer ends 70 adapted to engage the contacts and segments embedded in said wheel. The other ends of the brushes are secured to an insulating block 21 which is fastened to the end wall of the casing. When the code wheel is rotated, the brush 19 75

will alternately engage the segments and contacts on its side of the wheel, while the brush 20 will engage the alternately disposed segments and contacts located on its side. Due to the arrangement of the segments and contacts, it is obvious that when the brush 19 is engaging a series of contacts, the other brush 20 is riding on a segment. Similarly, when the brush 20 engages contacts, the brush 19 is contacting the segment on the opposite side of the code wheel. Since each successive series of contacts are on opposite sides of the code wheel and also since each successive segment is on the opposite side of said wheel, it is obvious that the positive and negative potential are caused to be on opposite sides of the code wheel. With the brushes in the position shown in Figure 5, rotation of the code wheel in a clockwise direction, will cause the brush 19 to successively engage the four contacts 14a, while the brush 20 is in constant engagement with the segment or sector 14b. The brush 19 thus makes and breaks four contacts on the negative side of potential while the brush 20 is making continuous contact on the positive potential. Continued rotation of the wheel causes the brush 19 to encounter the segment 16b which has positive potential on it, while the brush 20 makes and breaks the contacts 16a, having negative potential. A lead wire 19a leads from the brush 19 and a similar wire 20a leads from the brush 20, whereby when the code wheel is rotated and the brushes engage the contacts and segments, as explained, polarized current is sent out over said wires. In effect, the code wheel is a rotating pole-changer and sends out interrupted impulses of positive and negative electric potential, such impulses being created by the making and breaking of the contacts with the brushes. The high frequency interrupted impulses of alternatingly positive and negative polarity represent the digits or numerals of the telephone number of the station with which the code wheel 12 is associated.

For rotating the code wheel 12, a ratchet wheel 22 is fastened to one face or side of the code wheel and is rotatable on the stub shafts 13. A flat spring 23 surrounds the shaft having one end secured to said shaft, while its opposite end is fastened to the code wheel and unwinding of the spring rotates the wheel in a counterclockwise direction (Figure 1). Therefore, when the ratchet and code wheel are rotated in a clockwise direction, the spring is wound and exerts its pressure to urge the wheel in a counterclockwise rotation.

For rotating the code wheel in a clockwise direction so as to cause the contacts and segments to be engaged by the brushes 19 and 20 so as to transmit the alternately positive and negative high frequency impulses over the wires 19a and 20a, an operating pawl 25 has one end riding on the ratchet wheel 22. This end of the pawl is arranged to engage the teeth of the ratchet and when moved in the direction of the arrow in Figure 1, said pawl imparts a clockwise movement to the ratchet and to the code wheel secured to said ratchet. Movement of the pawl in an opposite direction causes said pawl to ride over the incline of the next adjacent tooth of the ratchet wheel so as to engage the straight side of the tooth, whereby further clockwise rotation of the code wheel may be accomplished. The code wheel is thus rotated in a step-by-step action and the amount of clockwise rotation which is imparted to the code wheel depends on

the number of contacts and segments on said wheel. These contacts and segments are varied in accordance with the numerals of the telephone number which they represent. As shown in Figure 5, the telephone number has only four numerals and therefore, only approximately one-half of the code wheel is taken up, whereby only one-half a revolution is necessary to cause all of the contacts and segments to engage the brushes 19 and 20. Different telephone numbers, having more or less numerals, will require a rotation of the code wheel through a different number of degrees.

For reciprocating the operating pawl 25, an armature 26 of a magnetic relay 27 is pivoted on a pin which extends through a bracket 28 mounted within the casing 10. The upper end of the armature is pivotally secured at 29 to the outer end of the operating pawl and each time the magnetic coil 27 is energized the armature 26 is attracted thereto, whereby the armature is swung to slide the pawl over one of the teeth of the ratchet wheel and permit it to engage the flat side of said tooth. A coiled spring 30 has one end fastened to the extended end of the armature while its opposite end is secured to a leg 31 which depends from an insulating block 32 secured to the underside of the bracket 28. The spring exerts its tension to constantly urge the armature away from the coil and therefore, when the coil is energized, the armature is swung under tension of the spring 30. Upon de-energization of the coil 27, the spring immediately swings the armature outwardly which moves the operating pawl in the direction of the arrow in Figure 1, and thus it will be seen that it is the force of the spring which imparts the clockwise rotation to the ratchet and code wheel. The coil 27 is merely utilized to slide the pawl back over the ratchet to permit it to engage the next tooth.

From the foregoing, it will be obvious that as the coil 27 is alternately energized and de-energized, the operating pawl 25 is reciprocated to rotate the ratchet wheel 22 and code wheel 14 in a clockwise direction. As the code wheel is rotated in such direction, the flat spring 23 which has one end secured to said wheel is wound, and to prevent reverse rotation of the wheel, while the operating pawl is slid to engage the next tooth, a retaining or escapement pawl 33 has its upper end engaged with the ratchet teeth. This pawl is pivoted on a pin 34 mounted in a bracket 35 which is fastened to the casing wall and a coiled spring 36 has one end secured to the lower end of the pawl. The spring holds the pawl in constant engagement with the ratchet teeth and prevents reverse rotation of the ratchet and code wheel while in such engagement.

The coil 27 which reciprocates the operating pawl 25 is energized by a battery circuit which is clearly shown in Figure 5. A lead wire 27a leads from one side of the coil while a wire 27b extends from the other side thereof. The wire 27a is connected to a switch blade 37 which is mounted in the insulating block 32 below the bracket 28. The blade overlies an elongate contact arm 38 which has its outer end disposed beneath an extension lug 39 formed on the lower end of the armature 26, whereby when the armature is swung to operate the pawl 25, the arm 38 is also swung into and out of engagement with the blade. The contact arm is connected by a wire 38a with a switch blade 40, which is arranged

to move into and out of engagement with a switch arm 41. The latter arm is connected to one side of the battery 42 by a wire 41a. The other side of the battery is connected by the wire 27b to the 5 other side of the coil 27.

Thus, it will be seen that the battery 42 supplies the current for energizing the operating coil 27. This current flows from one side of the battery through the wire 27b, through the coil 27, 10 blade 37, arm 38, blade 40 and arm 41 and then back to the other side of the battery to complete the circuit. If either one of the switches in the circuit are open, the coil 27 is not energized. The switch formed by the blade 40 and arm 41 is the 15 master control switch for the coil and is closed only when the code wheel is ready to operate, as will be hereinafter explained. Normally, with the coil 27 de-energized, armature 26 and pawl 25 are in the position shown in Figure 1, with the 20 switch blade 37 engaging the switch arm 38, and the arm 41 disengaging the contact 40.

When the master switch is closed, the blade 40 is engaged with the arm 41 and the battery circuit to the coil 27 is closed, whereby the coil is 25 energized and the armature 26 is attracted and swung to move the pawl 25 into engagement with the next tooth of the ratchet wheel 22 secured to the code wheel 14. The swinging of the armature also disconnects the contact arm 33 from the 30 blade 37, thereby breaking the battery circuit and de-energizing the coil 27. De-energization of the coil permits the coiled spring 30 to immediately swing the armature 26 outwardly to impart movement to the operating pawl 25 in the direction of the arrow in Figure 1, whereby the ratchet and code wheel are rotated. As soon as the armature has been swung outwardly, the arm 38 and blade 37 are again engaged to again energize the 35 coil 27. Thus, the coil is alternately energized and de-energized by its own armature and such action is continued until the rotation of the code wheel is completed, which is at the time when all contacts and segments on said code wheel have 40 been contacted by the brushes 19 and 20, and the alternately positive and negative electrical impulses have been transmitted over the wires 20a and 19a. Thus, it will be seen that when the 45 battery circuit to the coil 27 is closed by the master switch, which comprises the blade 40 and arm 41, the code wheel is rotated to set up and transmit the positive and negative impulses which represent the numerals of the telephone number.

For controlling the operation of the master switch, as well as for releasing the retaining pawl 33, a differential relay 50 is mounted below the coil 27 within the casing on a suitable bracket 51. The relay includes two windings 50-1 and 50-2, the former being arranged to be energized by central office equipment, as will be explained, 55 while the latter is energized by a battery circuit. The relay is provided with an armature 52 which is pivoted at its lower end to an ear 53 formed on the bracket. The armature is provided with an angular leg 54 which overlies the contact arm 41 of the master switch. When the relay is de-energized and in a normal position, the armature 60 is spaced from the relay and the contact arm 41 is disengaged from the blade 40.

The upper end of the armature 52 has one end 65 of an actuating bar 55 pivoted thereto and the opposite end of said bar is slotted at 56. A pin 57 in the extreme lower end of the release pawl extends through the slot 56 to connect the pawl and bar. When the armature and bar are in the 70 position shown in Figure 1, with the relay 50

de-energized, the pawl 33 is disengaged from the ratchet wheel 22 and the code wheel is free to be rotated by the spring 23. A bell crank lever 57 is mounted on the code wheel shaft 13 and has one arm 58 pivotally secured to the actuating bar 55, while its other arm underlies the operating pawl 25. With the bar 55 in the inactive position (Figure 1) the crank is swung so as to raise the pawl 25 out of engagement with the teeth of the ratchet wheel. 5

Coil 50-1 of the relay 50 is energized by wires 50a and 50b, as will be hereinafter explained, and such energization occurs when the connection from the calling to the called station is made through the central telephone office equipment. When the coil 50-1 is energized, the armature 52 of the relay is attracted whereby the bar 55 is moved to engage the pawls 25 and 33 with the teeth of the ratchet wheel 22. At the same time the contact arm 41 of the master switch is 10 engaged with the switch blade 40 to close the battery circuit to the coil 27 and operate the same, as has been described. 15

Below the master switch A which is actuated by the relay 50, a trio of switches B, C and D are provided. The switch B includes a switch blade 43 and a switch arm 44, the latter being connected to the arm 41 by an insulating bar 40'. The switch C includes a switch blade 53 and a switch arm 59, the latter being connected to the 20 blades 41 and 43 by the insulating bar 43'. The switch D includes a switch blade 60 and switch arm 61 and said arm is connected to the arms 59, 43 and 41 by the bar 40', whereby all of the switches are operated simultaneously. When the 25 relay 50 is energized the arms 41, 44, 59 and 61 are moved into engagement with their respective blades 40, 43, 58 and 60 to close the electrical circuits therethrough and when the relay is de-energized, said arms are simultaneously disengaged from their respective blades to open the 30 circuit therethrough. 35

The switch blade 43 of the switch B is connected by a wire 43a to one side of the coil 50-2 of the relay. The other side of the coil 50-2 is 40 connected by a wire 43b to a battery 45. A lead wire 45a extends from the battery to a fixed contact 43'. A switch arm 44' is normally engaged with the contact 43' and has its end disposed in the path of a radial pin 45' (Figure 1) which extends outwardly from the periphery of the code wheel 14. The pin is located on the periphery of the wheel so that when the rotation of the wheel is completed and the impulses, which represent the numerals of the telephone number have been 45 sent, said pin strikes the contact arm 44' to separate the same from the contact 43'. The switch 44' is connected by a wire 44a to the switch arm 44 of the switch B and manifestly, when the arm 44 is engaging its blade 43, the circuit to the coil 50-2 of the relay is completed. This circuit remains closed to hold the armature 52 inwardly of the relay 50 until the code wheel has completed its rotation, at which time the pin 45' engages the switch arm 44' to disengage the same from the contact 43' and thereby open the circuit to the coil 50-2 to de-energize said coil. This de-energizes the relay and permits the armature 52 to return to its normal position, which causes separation of the switch blades 40 and 43 from 55 their respective arms 41 and 44. Separation of the blade 40 and arm 41 breaks the battery circuit to the operating coil 27 and stops further rotation of the code wheel. 60

From the foregoing, it will be manifest that 65

the relay 50 is first operated by the energization of its coil 50-1, which coil is energized through the wires 50a and 50b which lead from the central office. As soon as the armature 52 is attracted, the switch B is closed and the circuit to the second winding 50-2 of the relay is closed to energize this second winding. The winding 50-2 remains energized until the circuit is broken by the separation of the blade 44' and contact 43' which separation occurs when the code wheel has completed its rotation. The second winding 50-2 and its separate battery circuit is provided to assure the relay 50 remaining energized throughout the rotation of the code wheel as the circuit through the wires 50a and 50b from the central office may be interrupted before said code wheel has completed its operation. Thus, the winding 50-2 and its associate parts provide positive means for assuring complete rotation of the code wheel.

The switch blade 53 of the switch C is connected to one of the calling station's line terminals 70 by a wire 52a, while the arm 59 which engages said blade is connected with the wire 20a, which leads from the brush 20. The wire 19a is connected to the switch arm 61 of the switch D, while the switch blade 60 of said switch is connected by a wire 60a to the other line terminal 71 of the calling station, as will be presently explained. Thus, it will be manifest that when the relay 50 is energized the switches A, B, C and D are operated or closed. The switch A closes the battery circuit to the operating coil 27 so as to rotate the code wheel, and the switch B closes the auxiliary battery circuit to the winding 50-2 of the relay, while the switches C and D electrically connect the brushes 19 and 20, which engage the contacts and segments of the code wheel, to the central office equipment, whereby the alternately positive and negative high frequency impulses may be transmitted over the central office equipment.

The central office equipment

From the foregoing, it will be seen that the calling station is provided with a transmitting unit T, whereby alternately positive and negative electrical impulses, which represent the telephone number of the calling station, are set up and transmitted through the switches C and D. In order to describe how these impulses reach the called station, it is necessary that a general outline of the central office equipment of the usual telephone system be given. In Figure 6, the transmitting unit is illustrated as connected with the usual Strowger step-by-step automatic telephone system which is now in general use. For a comprehensive understanding of the details of this system, reference is made to "Telephone theory and practice" by Kempster B. Miller, 1st edition, 1933, published by McGraw Hill Company, and this volume is quoted hereinafter, with regard to the action and operation of the telephone equipment illustrated.

In Figure 6 of the drawings, a telephone connection between the calling station and called station is shown and in this figure S indicates the calling station, O a portion of the central office equipment and S' indicates the called station. The transmitting unit T, hereinbefore described, is connected with the calling station S while a receiving unit R is connected with the called station S', as will be explained. For the sake of clarity, the complete central office equipment of first, second and third selectors which

merely extend the calling station's trunks selectively to a final selector or connector is not shown; the final selector is shown complete with all essential relays and magnets except the test and supervisory wiring, which do not enter into the operation at this time.

The calling station includes the line terminals or normals 70 and 71 which are adapted to be connected to the main trunks 72 and 73 of the central office equipment when the receiver is lifted off its hook 14 at said calling station. The lifting of the hook also causes the electrical current to flow through a line relay (not shown) which is associated with the calling station at its terminals at the main distributing frame of the central office equipment. This line relay is energized by the central office battery and starts a series of operations preparing and selecting office trunk circuits to the first numerical switch or line finder equipment. When the person calling hears the "dial tone", he proceeds to operate the dial 76 to dial the number of the station he desires. The impulses from the dial 76 progressively extend the calling station's line over central office trunks to first, second and third selectors (not shown) and thence to the final selector or connector O. This final selector has access to the multiple of all the lines and selects the line called for in the usual manner. When this last selector has been actuated, the calling station's lines 70 and 71 are metallically extended through the trunks 72 and 73 to upper and lower contacts 77 and 78 of a relay 79 in the connector. If the called line is busy, a busy signal will be sent back over the trunks 72 and 73 and to the lines 70 and 71 of the calling station S. The equipment for setting up this busy signal is not shown, as it forms no part of the present invention.

If the called station S' is not busy, the last relay 80 in the final selector O is energized and connects the called station's lines 70' and 71', through the office trunks 72' and 73' to upper and lower armatures 81 and 82. Thus, when the relay 80 has been energized, the calling station S has its line 70 connected to the trunk 72 which is connected to the contact 77 of the relay 79. The trunk 72 is also connected to the trunk 72' through a condenser 83 and the trunk 72' is, of course, connected with the line 70' of the called station S'. The other line 71' of the called station has connection with the trunk 73' which leads to the armature 78 of the relay 79. This trunk is also provided with a condenser 83' of suitable capacity. Normally, this armature is engaged with a ground wire 84 and therefore, when the last relay 80 in the connector is operated, the connection between the lines 70 and 71 of the calling station S and line 70' and 71' of the called station S', is not complete because the circuit is grounded to the wire 84.

However, when the relay 80 is energized, it closes the circuit between the ringing generator 85, which is common to all telephones, and the current from said generator flows through a wire 85' which leads to a contact 86, said contact being normally engaged by the upper armature of the relay 79. Thus, it will be seen that the calling lines 70 and 71 and the called lines 70' and 71' are open at the upper and lower contacts 77 and 78 of the relay 79 during the ringing period. These lines will be closed only when the armatures 79a and 79b of the coil 79 are swung to engage said contacts and such swinging of the armatures occurs upon energization of the relay 75

79. The energization of the relay 79 is accomplished when the hook 74' of the called station S' is lifted. Therefore, when the called party answers his telephone, the connection between the stations S and S' is complete.
- 5 At the moment that the relay 80 is energized, the ringing current from the generator 85 is impressed on the line of the called station S' and as soon as the called station answers by lifting 10 the hook 74', the ringing generator 85 is disconnected. At the instant that the ringing current is impressed on the called line and during 15 the ringing period, but before the called station answers, the transmitting unit T is set into operation and the alternately positive and negative impulses, which represent the telephone number 15 of the calling station, are superimposed upon the ringing current.

The transmission of impulses

- 20 As has been stated, the transmitting unit T is connected with the calling station S and such connection is clearly shown in Figures 5 and 6. The differential relay 50 may be termed the starting relay, for said relay must be energized to close the switches A, B, C and D in order to set 25 the transmitting unit in operation. This relay is supplied with current through the wires 50a and 50b, the former being connected to a suitable ground 87. The latter wire 50b has a condenser 88 connected therein and has its opposite end connected to the ungrounded side of the trunk 70 of the central office equipment. When the 30 ringing current is impressed on the called station, the audible ringback current is impressed on the calling station, flowing through the condenser 88, trunk 72, and line 70 of said calling station. This current flows through the wire 50b, condenser 88 and to the coil 50-1 of the relay 50, whereby said relay is energized to attract its 35 armature 52 and close the switches A, B, C and D to set the transmitting unit T into operation. Thus, when the ringing period begins, the transmitter is actuated.
- 40 As has been explained, the closing of the switch B closes the auxiliary battery circuit to the coil 50-2 of the relay 50 and said relay is thereby maintained energized during the complete rotation of the code wheel 14. Such rotation of the code wheel sets up and transmits alternately positive and negative high frequency 45 impulses over the wires 60a and 58a, which lead from the switch blades 60 and 58 of the switches C and D. The wires 60a and 58a are connected to the line terminals 70 and 71 of the calling station S (Figure 6), at the main distributing frame at the central office. High frequency current from the generator 15 is connected to the 50 commutating contacts and segments on the code wheel and in rotating, the wheel causes make and break contacts to be made and this interrupted current is impressed on the lines 70 and 71 and on the office trunks 72 and 73. It is noted that a battery 15c may be substituted for the generator 15 as a source of current for the impulses and this battery could be connected to the wires 15a and 15b by means of a switch 15d, as shown in Figure 1. The switch 15d is shown in this figure as connecting the generator 15 to the lead wires 55 15a and 15b but may be readily moved to the position shown in dotted lines to cut out the generator and connect the battery in the circuit.
- 60 From the foregoing, it will be seen that as soon as the relay 80 of the central office connector O is energized at the time the ringing period be-

gins, the relay 50 of the transmitter T is actuated to set the code wheel 14 and its associate parts into operation. The alternately positive and negative impulses of a high frequency current are thus impressed through the wires 58a and 60a 5 on the lines 70 and 71 of the calling station S and on the office trunks 72 and 73 thence through the condenser shunts 83 and 83' and onto the lines 70' and 71' of the called station S'. These impulses are received at the station S' and are 10 transposed into visible numerals by the receiving unit R, as will be presently explained. It is noted that impulses are sent or transmitted immediately upon operation of the relay 80 of the office connector O, which is during the ringing 15 period. The relay 79 of the connector O has not operated, since this relay is energized when the hook 74' of the called station S' is lifted. Therefore, the high frequency alternately positive and negative impulses may be said to be superimposed 20 on the ringing circuit.

The receiving unit

The high frequency positive and negative polarity impulses are, thus, on the lines 70' and 71' 25 of the called station S' and these impulses are received by the receiving unit R which is located at the called station. The construction of the receiving unit is shown in Figures 7 to 11, while the wiring of said unit is clearly illustrated in 30 Figure 11.

The receiving unit includes a casing or housing 100 (Figures 7 and 11), which is preferably constructed of electrical insulating or non-conducting material and said casing is preferably located in close proximity to the telephone instrument of the called station S'. A double winding relay 101 is mounted within the casing 100 and this relay has one winding which is energized when the relay 80 in the connector O is energized to make line selection in the line multiple of the central office equipment. When this relay 101 is energized, it attracts its armature 102, whereby said armature operates a switch 102' to close a circuit to the second winding of 45 said relay, whereby a second armature 103 is attracted. This second armature operates a switch 103' which has connection with the line 70' of the called station S', over which the high frequency impulses travel, and is adapted to engage a contact 104 when moved inwardly by energization of the second winding of the relay. The contact 104 is connected to the windings 105 and 106 of a polarized relay 107, which relay is mounted within the casing 100 at the lower end thereof. A pivoted armature 108 is located adjacent the ends of the windings 105 and 106 and is adapted to be attracted to one or the other of said windings, depending upon which one is energized.

The winding 105 is arranged to be energized by positive polarity while the winding 106 is arranged to be energized by negative polarity. Therefore, when the connection between the calling and called stations S and S' is made and the relay 101 is operated, the positive and negative polarity pulsations traveling over the lines 70' and 71' of the called station are conducted through the switch 103' and the contact 104 to the windings 105 and 106. The first impulses, being positive, represent the first numeral or digit of the calling station, and energize the positive winding 105, a number of times in accordance with the number of impulses, whereby the armature 108 is swung a similar number of 70 75

times in one direction. As shown, the code wheel 14 in the transmitting unit first sends out four positive impulses, thereby energizing the winding 105 four times and swinging the armature 108 four times. This indicates that the first digit or numeral of the calling station is four. The negative winding 106 is then actuated a predetermined number of times, in accordance with the number of negative impulses transmitted, whereby the armature 108 is swung in an opposite direction a given number of times. This swinging of the armature in an opposite direction by the negative impulses indicates the second digit of the telephone number of the calling station S. As illustrated, this second digit is also four. The third digit is represented by positive impulses, the fourth by negative impulses, and so on, whereby the polarized relay 107 is operated alternately by positive and negative impulses throughout the rotation of the code wheel and until the entire telephone number of the calling station, as represented by the impulses, is transmitted. The armature 108 is, of course, swung in accordance to the energization of the windings 105 and 106 of the relay 107.

The armature 108 is provided with an extension or arm 109 (Figure 10) which is, preferably, integral therewith so as to swing simultaneously therewith. The arm is confined between switch blades 110 which have an inherent resiliency, whereby said blades urge the arm to an upright position to normally hold the armature 108 away from the windings 105 and 106. When the winding 105 is energized, the armature 108 and arm 109 are swung so that one of the blades 110 is swung into engagement with a contact arm 111. Energization of the other winding 106 swings the armature and blade in an opposite direction to engage the other blade 110 with a contact arm 112. The blades 110 are connected to a common ground, while the contacts 111 and 112 are connected with a register, as will be explained. Thus, the direction of movement of the armature and the number of times of such movement, controls the actuation of a register, whereby the swinging of the armature is transposed into visible numerals, indicating the telephone number of the calling station as represented by the transmitted impulses.

50 The register mechanism

The register is located within the casing 100 and includes a plurality of rotatable disks 113, 113a, 113b, 113c, 113d and 113e which disks are rotatably mounted on a transverse shaft 114 which extends through the casing (Figures 7 and 8). The disks are provided, one for each numeral or digit of the telephone number and are rotated in accordance with the positive and negative pulsations energizing the relay 107 and actuating the armature 108. Each disk has the numerals 1 to 0 displayed on its periphery and one of these numerals is visible through a window 100' provided in the top of the casing 100 above the disks.

55 For rotating the disks, a plurality of magnetic relays or coils 115, 115a, 115b, 115c, 115d and 115e, are mounted on a support 116 within the casing 100 and each coil controls the operation of one of the disks. As the operating connection between each coil and its respective disk is exactly the same, a description of one will suffice.

Each coil 115 to 115e has an armature 117 which has its lower portion pivoted to the end 70 of the support 116, the extreme lower end of said

armature having one end of a coiled spring 120 fastened thereto. The other end of the spring is secured to an ear 120' which depends from the support and the spring 120 exerts its tension to constantly urge the upper end of the armature 117 away from the coil 115. When the coil is energized the armature is drawn inwardly under tension of the spring 120 and when de-energized, the spring immediately swings the armature outwardly.

An operating pawl 121 has one end pivoted to the upper end of the armature 117 and its opposite end rides on a ratchet wheel 122 which is secured to the register disk 113. The pawl is arranged to engage the teeth of said ratchet wheel 15 and impart rotation thereto, in the same manner as the pawl 25 imparts rotation to the ratchet wheel 22 of the transmitting unit. Each time the coil 115 is energized, the disk 113 is rotated the distance of one tooth on the ratchet wheel 20 122 and the teeth on said wheel are arranged to coincide with the numerals on the periphery of the disk, whereby each movement of said ratchet wheel by means of the pawl 121 causes the next successive numeral on the disk to become 25 visible through the window 100' in the casing. Thus, if the coil 115 is energized four times, the pawl 121 is reciprocated four times to move the numeral four on the periphery of the disk 113 into view through the window 100'. 30

A flat spring 123 (Figures 8 and 9) is disposed adjacent the disk 113 and surrounds the shaft 114. This spring has one end secured to the shaft and its opposite end fastened to the disk and said spring is wound as the pawl 121 rotates 35 the wheel, whereby it constantly urges the disk in a reverse direction. For preventing such reverse rotation while the pawl 121 is reciprocating, a retaining or escapement pawl 124 engages the teeth of the ratchet wheel. This pawl operates 40 in a manner similar to the escapement pawl 33 of the transmitting unit and is pivoted at its lower end on a pin 125. A coiled spring 126 has one end secured to the pawl below the pivot and its opposite end is fastened to the casing wall, 45 whereby the spring holds the pawl in engagement with the teeth of the ratchet wheel.

From the above, it is manifest that the relays or coils 115 to 115e control the rotation of the register disks 113 to 113e, whereby the numerals 50 visible through the window 100' are set up through the operation of these relays. The relays are energized by means of the contacts 111 and 112 and the switch blades 110, which blades are moved by the armature 108 of the polarized 55 coil. The wiring details and hook-up between the contacts 111 and 112 and the relays 115 to 115e will be hereinafter explained. At this point, it is noted that when the armature 108 is swung by the energization of the positive winding 105 of 60 the relay 107, the blade 110 is engaged with the contact 111. Such engagement closes an electrical circuit to the first relay or coil 115, whereby a rotation is imparted to the first register disk 113. This disk is rotated so long as positive impulses are carried to the winding 105 and the coil 115 is energized the number of times that the blades 110 engage the contact 111, whereby the disk 113 is rotated to indicate the number of such instances. As illustrated in the drawings, four positive impulses pass to the winding 105, which means that the blade 110 engages the contact 111 four times, thereby energizing the coil 115 four times and rotating the disk 113 so as 70 to move the numeral "four" on its periphery 75

into alignment with the window 100' in the casting.

- After the disk 113 has been actuated in this manner, the negative impulses transmitted from the unit T, energize the winding 106 to swing the armature 108 so that the blade 110 engages the contact 112. The engagement of this contact closes a circuit to the next coil 115a and the negative impulses energize this coil to impart rotation to the next register disk 113a, whereby the number of negative impulses are transposed into a visible numeral. After the coils 115 and 115a have been actuated, the circuit thereto is opened, as will be explained, and therefore the next positive impulses received by the winding 105 again swing the blade 110 into engagement with the contact 111; the second closing of this contact does not again operate the coil 115 but operates the coil 115b, which rotates its disk 113b. Similarly, the next engagement of the blade 110 with the contact 112 actuates the next coil 115c, and so on until all of the coils and register disks, necessary to record the transmitted impulses, have been operated. Thus, it is obvious that the alternately positive and negative polarity impulses actuate the coils 115 to 115e in successive order to set up on the registering disks 113 to 113e, the telephone number of the calling station S. The disks may vary in number depending upon the number of digits in the telephone numbers in the particular locality where the system is employed.

Referring next to Figure 11 wherein is shown the electrical wiring diagram illustrating the connection between the contact arms 111 and 112 and the registering mechanism, it will be seen that the contact arm 111 is connected by a wire 111a to a metallic actuating arm 127 of the disk 113a. This arm has its lower end secured in an insulating block 128 mounted on the casing wall, while the upper end of said arm carries a roller 129 which rides on a circular cam 130, formed integral with one side of the disk 113a. The cam has a flat portion 131 and when said roller engages this flat portion, the arm 127 is swung inwardly to engage a contact blade 132. When the roller is riding the periphery of the disk 113a, the arm 127 is swung outwardly to engage a contact blade 133. It is noted that each of the disks 113 to 113e is formed with the cam 130 and the arm 127, as well as the blades 132 and 133 and it is through the medium of these parts, that the register disks are operated successively by the alternately positive and negative impulses sent out from the transmitting unit. Normally, all of the rollers 129 are engaging the flat portion 131 of their respective cams 130, whereby the arms 127 are engaging the blades 132.

As explained, the contact 111 above the polarized relay 107 is connected by the wire 111a with the swinging arm 127 of the relay 113a. This arm is engaged with the blade 132 and the current flows through this blade and through a wire 132a to one side of the relay coil 115. The other side of said coil is connected to a common supply wire 115', which is connected to the line normal 70' of the station S'. Therefore, when the positive impulses are transmitted to the winding 105 of the relay 107, the contact 111 is engaged by the blade 110 and the circuit to the first relay coil 115 is closed to operate the first register disk 113. The coil 115 is energized as many times as the contact 111 is engaged by the blade 110, which is dependent upon the number of positive impulses in the first transmitted series. It is noted

that when the first register disk 113 is actuated, the arm 127, engaging the flat surface 131 of the cam 130 on said disk, rides off of said portion and onto the periphery of the disk, whereby the arm 127 associated with the disk 113 is disengaged from the blade 132 and engaged with the arm 133.

When the first series of negative impulses energize the other windings 106 of the relay 107, the blade 110 is engaged with the contact 112. 10 This contact 112 is connected by a wire 112a with the contact blade 133 of the first disk 113. The blade 133, as explained, is engaging the arm 127 and the current flows through this arm 127 and through a wire 127a to the arm 127 of the third register disk 113b. Since this third disk has not yet been rotated, its arm 127 is engaging the blade 132 thereof and the blade 132 is connected through a wire 132aa with the second relay coil 115a. The relay 115a has its other side 20 connected to the common supply 115'. Thus, it will be seen that when the armature 108 of the relay 107 is swung by the negative impulses to engage the contact arm 112 with the blade 110, the second coil is actuated. It is pointed out that 25 to reach the coil 115a, the current must flow through the arm 127 and blade 133 of the first register disk 113, whereby said first disk must be operated before the second disk 113a can be rotated. The current must also flow through the arm 127 and blade 132 of the following or third disk 113b which assures that the third disk has not been actuated.

After the first and second coils 115 and 115a have been actuated, the next series of positive 35 impulses to the relay 107 again swings the blades into engagement with the contact 111. The current flows over the wire 111a to the arm 127 of the second disk 113a but cannot again pass through the blade 132 to the first coil 115, as this 40 blade has been disengaged from the arm by rotation of the disk 113a. Instead, the current flow through the blade 133 of the disk 113a, then through arm 127 and blade 132 of the fourth disk 113c and finally to coil 115b to actuate the 45 third disk.

The next series of negative impulses to the relay closes a circuit to the coil 115c of the fourth disk 113d, passing through the arms 127 and blades 133 of the disks 113, 113b and 113d to reach the coil 115c. The next positive series of 50 impulses again connects the blade 110 to the contact 111 and the current flows to the coil 115d through the arms 127 and blades 133 of the disks 113a and 113c. The next series of negative impulses 55 actuate the last coil 115e, the current passing through the arms 127 and blades 133 of the disks 113, 113b and 113d.

An additional contact blade 134 is provided adjacent the next to the last register disk 113d 60 and this blade is adapted to be engaged by a contact arm 135 which arm is secured to the arm 127 of the disk so as to be movable therewith. When the disk 113d is inactive, and before it has been rotated this contact is in engagement with the blade. The blade 134 is connected by a wire 134a to the contact 104 of the armature 103 which is actuated by the relay 101, while the blade 135 is connected to the ground at the blades 110 through a wire 135a. The contact 134 is separated from the blade 135 when the disk 113d is rotated.

The contact blade 127 of the last disk 113e is connected with the wire 135a while its contact 132 is connected to the wire 134a, whereby before 75

the disk 113e is rotated, the circuit is closed between the blade and contact. However, when the last disk 113e is actuated, the blade and contact are separated and any further impulses which might be transmitted to the relay 107 will have no effect on the registers.

The register disks are actuated, as described, to set up the numerals or digits of the telephone number of the calling station S, as represented by the high frequency alternately positive and negative impulses transmitted to the polarized relay 107. The registering is done simultaneously with the ringing current and is superimposed thereon; however, the numerals are set up practically during the initial ringing signal. Since the polar relay 107 is not tuned to the ringing current it will not operate on it, nor will the ringing coils be effected by the high frequency code current, since said coils are not tuned to that frequency, having different impedance values.

The double winding relay 101, which attracts the armature 103, so as to provide a path for the high frequency current to the polar relay 107, is of the slow release type, whereby the armature 103 is held in its operative position for a sufficient length of time to permit the register disks to operate. Release of the armature breaks the contact to the polar relay 107 and disconnects the register operating coils 115 to 115e from their battery supply. As explained, further operation of the register is not possible even though additional high frequency impulses may be transmitted to the relay 107 and therefore, the number set up by the disks remains so until the disks are returned to original starting position by the lifting of and returning of the receiver hook at the called station S', as will be presently explained.

The register clearing mechanism

From the foregoing, it is obvious that the telephone number of a calling station is set up at the called station and if the subscriber is absent when the call is made, he can readily note the number which has called him during such absence. For clearing the register and returning the disks 113 to 113e to their starting position, a double wound release relay 140 is mounted within the casing 100 below the coils 115. This relay has a winding 141 and winding 142, the former being arranged to attract an armature 143 and the latter adapted to attract an armature 144. The armature 143 is pivoted to an ear 145 and has a laterally directed leg 146 at its lower end, whereby when the armature is swung, the leg is also swung. The leg is confined between switch blades 147 and 149 and when the armature 143 is in an outer position, the leg moves the upper blade 147 into engagement with a contact arm 148. When the winding 141 is energized, the armature is attracted and the leg 147 disengages the blade 147 from the contact arm 148 and engages the blade 149 with a contact blade 150. A third blade 151 is secured to the blade 149 and is movable therewith, being arranged to engage a contact arm 152 when the armature 143 is attracted by the energized winding 141.

For latching the armature 143 in its inner position (Figure 7) a latching bar 153 overlies the relay 140 and has a pawl 154 at one end for engaging over the upper end of the armature. The opposite end of the bar 153 is pivoted on a transverse bar and the upper end of the armature 144 of the winding 142 is secured thereto. When the armature 144 is attracted, the bar is swung upwardly to release the armature 143. A pin 155

extends upwardly from the bar 153 and is arranged to engage a contact blade 156, which blade normally engages a contact arm 157. When the bar is latching the armature 143, the blade and arm are engaged to close an electrical circuit therebetween, but when the armature 144 is swung inwardly, due to the energization of the winding 142, the bar 153 is swung upwardly to disengage said contacts.

The armature 144 has its lower end fastened by a link 158 to an angular release member 159. The member is provided with a pin 160 slideable in a slotted supporting member 161 which depends from the support 116 and when the armature is swung, the member is moved laterally within the casing. The extreme outer end of the member is connected with the lower end of the retaining pawl 124 by means of a shaft 161' and slot 162, the latter being in the member. The shaft is connected to all of the pawls 124 of the disks by the shaft 161' and when the member is moved by the swinging of the armature 144, all of the pawls 124 are disengaged from the ratchet wheels 122. A bell crank 163 is provided for each operating pawl 121, being pivoted on the disk shaft 114, and the upper arms of said bell cranks extend beneath the pawls 121. The lower arms of said bell cranks are connected by a transverse shaft 164 which is secured to the member 159. With such arrangement, movement of the member by means of the armature 144 simultaneously disengages the pawls 121 and the pawls 124, whereby the flat springs 123 may return the disks to a starting or normal position. The reverse rotation of the disks is limited by a peripheral pin 165 which strikes the underside of the top of the casing 100 (Figure 7).

For operating the release mechanism when the hook 74' of the called station S' is lifted so as to clear the register disks 113 to 113e, a pair of contacts 166 and 166' are provided above the hook and a second pair of contacts 167 and 167' are provided below the hook. Normally, the hook is in a lowered position in engagement with the contacts 167. One of the contacts 167 is connected by a wire 167a with the winding of the operating relay 101, which relay actuates the armatures 102 and 103, as has been explained. The other contact 167' is connected by a wire 151a to the switch blade 151 below the relay 140. When the hook is raised, the circuit to this relay is opened at the contact 167, whereby said relay 101 is inoperative so long as the hook is raised.

The raising or lifting of the hook 74', not only disengages the contacts 167 and 167', but also engages the upper contacts 166 and 166'. The upper contact 166 is connected through a wire 166a with the switch blade 147 which is normally in engagement with the arm 148. The contact 148 is connected by a wire 148a with one side of the winding 141 of the relay 140, the opposite side of said winding being connected by a wire 141a to the line normal 71' of the station S'. Thus, when the hook is raised to engage the contact 166, the current is conducted to the winding 141 to attract the armature 143 and swing the same. Swinging of the armature causes the upper end to engage beneath the pawl 154 of the latch bar 153 so as to lock the armature in its inner position and also the leg 146 of said armature disengages the blade 147 from the contact arm 148 and engages the blades 149 and 151 with their respective arms 150 and 152. Disengagement of the blade 147 and contact 148 breaks the circuit to the winding 141 to de-energize the same but

the armature 143 cannot swing away from the relay because of its latched condition. This condition of the armature 143 prepares a circuit to the other winding of the relay 140 when the hook 74' is again lowered by placing the receiver on said hook.

When said hook is again lowered, the current flows through the contact 167' and wire 151a to the blade 151. This blade is engaging the arm 152; being held so by the locked armature 143, and a wire 152a leads from the arm 152 to one side of the winding 142 of the relay 140. The other side of this winding is connected by a wire 142a to the contact arm 157 which is located above the latch bar 153. This arm is normally engaging the blade 156 and said blade is connected through a wire 156a with the blade 149 below the relay. The blade is held in engagement with the switch arm 150, which arm is connected by a wire 150a to the line normal 71' of the station S'. Thus, it will be seen that when the hook 74' is lowered, by replacing the receiver of the instrument thereon, the current flows to the winding 142 of the relay 140, passing through the blade 151, arm 152, blade 156, arm 157, blade 149 and arm 150. If any one of these blades are out of engagement with their respective arms, the circuit to the winding 142 is not complete.

30 The energization of the winding 142 attracts its armature 144 and moves the release member 159, whereby the pawls 121 and 124 are disengaged from the register disks 113 to 1113e, said disks being returned to their original or start-35ing positions by the flat springs 123. Swinging of the armature 144 also raises the latch bar 153 to disengage the bar from the armature 143, permitting said armature to swing away from the winding 141. Upward movement of the latch bar 40 153 disengages the blade 156 from its arm 157 which breaks the circuit to the winding 142, and all of the parts associated with the relay 140 are returned to a normal, or starting, position.

From the foregoing, it will be seen that the 45 telephone number of a calling station is recorded or registered during the ringing period. This registration remains visible until the subscriber at the calling station lifts his receiver, at which time the release mechanism is prepared for operation. Replacement of the receiver on the hook, resulting in downward movement of said hook actuates the release mechanism and clears the register, placing the same in readiness for the next recording.

55 Up to this point the operation of the transmission to, and indication of, calling subscriber's numbers at the called station is limited in its scope to setting up only one set of numbers; in other words, only one call can be registered at the called station. Any subsequent calls from the same or other sources would not be registered and would therefore be lost.

Therefore, in order to enlarge its scope and provide facilities for transmittal and reception 60 of two or more incoming calls at the called station it is only necessary to provide two or more additional groups of registering relays, similar to the first group, together with their associated ratchet and digit wheels, and releasing mechanisms. All groups will be cleared by the master clearing relay at the subscriber's station as in the single registration by the double relay 140.

To accomplish the visual registration of two or more calls to the same subscriber's station 75 there are provided as many multiple groups of

registering relays as it is desired to have calls registered. Any number may be installed to suit traffic conditions. Reference may now be had to Figure 6. To the cam 130 of the last operable relay 1113e of the first group is added an additional make and break contact or switch 127a. 5 Battery from the line serving the first group of relays is brought to one contact of this switch while the other terminal of this contact serves the battery feed to the second group of registering relays. The corresponding last relay in this second group is similarly equipped with a switch 127b serving battery to a third group of registering relays and the last relay of each succeeding group has a similar switch serving each 10 following group of relays, etc., for any number of groups. Ground is multiplied through the relay groups as are also the negative and positive impulse bus bars from the contacts on the polar relay 107.

The operation is as follows: After the first call number has been received and registered by the first group of relays, as previously described, the last operable relay in the first group closes the contacts of the switch 127a and puts battery 25 on the second group of relays. The next call will not effect the first group since all coil contacts are open at the cams 130 but it will effect the second group. This group will then proceed to follow the impulses sent to it from the polar 30 relay 107 and set up the second called numbers. The last operable relay in the second group closes its back contact and puts battery on the third group preparing it for the reception of the third calls, etc. Figure 6 shows the wiring arrangement of a two call registration unit. Each group of registering relays receives its battery supply 35 through contacts from the same central office battery brought to it progressively by the operation of the cam contacts from the preceding 40 group.

There is no limit to the number of groups or relays that may be provided. A private branch exchange may have a greater number than an individual. No attempt is made in this application 45 to prescribe any particular size or mechanical features of the units, as this is mainly subject to shop methods of different manufacturers.

Upon the called subscriber returning he will make note of all calls set up in his register; he 50 then proceeds to call any one of these or another number. The numbers as set up will remain visible during his first conversation; when he hangs up, the clearing out relay 140 will clear all registrations from all the relays and set them back 55 to zero or starting positions.

The above description and outline of operation covers the application of the transmission and reception of calling numbers to called stations to the step-by-step method of automatic telephone operation, but obviously, the invention may be adapted to any type of telephone system, either 60 automatic or manual.

The foregoing description of the invention is explanatory thereof and various changes in the 65 size, shape and materials, as well as in the details of the illustrated construction may be made, within the scope of the appended claims, without departing from the spirit of the invention.

What I claim and desire to secure by Letters 70 Patent is:

1. The method of transmitting the telephone number of a calling station which includes, setting up electrical impulses representing the number of the calling station, transmitting the im- 75

5 pulses to the called station, receiving said impulses at the called station, transposing the electrical impulses into visible numerals, registering the numerals at the called station, and clearing the registered numerals when the telephone instrument at the called station is used to make a subsequent call.

2. The method of transmitting the telephone number of a calling station to a called station 10 which includes, setting up electrical impulses which represent the number of the calling station when the connection between the stations is made, superimposing the impulses on the ringing circuit of the called station, receiving said impulses at said called station, transposing the electrical impulses into visible numerals, registering the numerals at the called station, and clearing the registered numerals when the telephone instrument at the called station is used.

20 3. The method of transmitting the telephone number of a calling station to a called station which includes, setting up electrical impulses of alternately positive and negative polarity which represent the number of the calling station when 25 the connection between the stations is made, superimposing the impulses on the ringing circuit of the called station, receiving said impulses at said called station, and transposing the impulses into visible numerals to indicate at the called station the number of the calling station.

40 4. A telephone recording system for transmitting the telephone number of a calling station to a called station including, means for setting up electrical impulses which represent the number 35 of the calling station, means for transmitting said impulses to the called station during the ringing period, and means at the called station for receiving said impulses and transposing the same into visible numerals, whereby the telephone number of the calling station is recorded at the called station.

45 5. A telephone recording system for transmitting the telephone number of a calling station to a called station including, means independent of the telephone instrument at the calling station for setting up electrical impulses which represent the number of the calling station, means for transmitting said impulses to the called station, means at the called station for receiving said 50 impulses, and a register at the called station actuated by the receiving means for transposing the electrical impulses into visible numerals to record the telephone number of the calling station.

55 6. A telephone recording system for transmitting the telephone number of a calling station to a called station including, means associated with the calling station for setting up electrical impulses which represent the number of the calling station, means for transmitting said impulses to the called station, means at the called station for receiving said impulses, a register at the called station actuated by the receiving means for transposing the electrical impulses into visible numerals to record the telephone number of the calling station, and means for clearing said register when the telephone instrument at the called station is subsequently used.

70 7. A telephone recording system for transmitting the telephone number of a calling station to a called station including, means associated with the calling station for setting up electrical impulses which represent the number of the calling station, means for superimposing the electrical impulses on the ringing circuit of the called station whereby said impulses are transmitted to

said called station, means at the called station for receiving said impulses, and means for transposing the same into visible numerals to record the telephone number of the calling station.

8. A telephone recording system for transmitting the telephone number of a calling station to a called station including, means for setting up electrical impulses which represent the number of the calling station, means for superimposing the electrical impulses on the ringing circuit of the called station whereby said impulses are transmitted to said called station, means at the called station for receiving said impulses, means for transposing the same into visible numerals to record the telephone number of the calling station, and means for clearing the recording when the telephone instrument at the called station is subsequently used.

9. A telephone recording system for transmitting the telephone number of a calling station to a called station including, means associated with the calling station for setting up electrical impulses which represent the number of the calling station, means for superimposing the electrical impulses on the ringing circuit of the called station whereby said impulses are transmitted to said called station, means at the called station for receiving said impulses, and a register at the called station actuated by the receiving means for transposing the electrical impulses into visible numerals to record the telephone number of the calling station.

10. A telephone recording system for transmitting the telephone number of a calling station to a called station including, means associated with the calling station for setting up electrical impulses which represent the number of the calling station, means for superimposing the electrical impulses on the ringing circuit of the called station whereby said impulses are transmitted to said called station, means at the called station for receiving said impulses, a register at the called station actuated by the receiving means for transposing the electrical impulses into visible numerals to record the telephone number of the calling station, and means for clearing said register when the telephone receiver at the called station is lifted and replaced subsequently using the instrument at the called station.

11. A telephone recording system for transmitting the telephone number of a calling station to a called station including, means associated with the calling station automatically actuated when the connection between the stations is made for setting up electrical impulses of alternately positive and negative polarity, which impulses represent the number of the calling station, means for transmitting said impulses to the receiving station, a polarized relay at the receiving station actuated by the electrical impulses, and means operated by said relay for transposing the impulses into visible numerals to record the telephone number of the calling station.

12. A telephone recording system for transmitting the telephone number of a calling station to a called station including, means associated with the calling station and actuated when the connection between the stations is made for setting up electrical impulses of alternately positive and negative polarity, said impulses representing the number of the calling station, means for transmitting said impulses to the receiving station, a polarized relay at the receiving station actuated by the electrical impulses, a register operated by said relay for transposing the electrical impulses

into visible numerals to record the telephone number of the calling station, and means for clearing said register when the telephone instrument of the called station is subsequently used.

- 5 13. A telephone recording system for transmitting the telephone number of calling stations to a called station including, means associated with the calling station for setting up electrical impulses which represent the number of the calling station, means for transmitting said impulses to the called station during the ringing period, means at the called station for receiving said impulses, a plurality of registers at the called station actuated by the receiving means for transposing the impulses into visible numerals, and means for operating said registers independently and in a desired order to register the telephone numbers of a plurality of calling stations at the called station.
- 10 14. A telephone recording system for transmitting the telephone number of calling stations to a called station including, means actuated when the connection between the stations is made for setting up electrical impulses of alternately positive and negative polarity, said impulses representing the number of the calling station, means for transmitting said impulses to the receiving station, a polarized relay at the receiving station actuated by the electrical impulses, a plurality of registers at the called station actuated by the relay for transposing the received electrical impulses into visible numerals, and means for operating the registers one at a time in a desired order to record the telephone numbers of a plurality of calling stations at the called station.
- 15 15. A telephone recording system for transmitting the telephone number of a calling station to a called station including, means associated with the calling station and actuated when the connection between the stations is made for setting up electrical impulses of alternately positive and negative polarity, said impulses representing the number of the calling station, means for transmitting said impulses to the receiving station, a polarized relay at the receiving station actuated by the electrical impulses, a plurality of registers at the called station actuated by the relay for transposing the received electrical impulses into visible numerals, means for operating the registers one at a time in a desired order to record the telephone numbers of a plurality of calling stations at the called stations, and means for clearing all the registers when the telephone instrument at the called station is subsequently used.
- 20 16. The combination with an automatic telephone system wherein calling and called stations are connected through central office equipment of a recording system including, means associated with the calling station and automatically actuated when the connection between stations is made for setting up electrical impulses which represent the telephone number of the calling station, said means being so connected to the central office equipment through the calling station that the electrical impulses are transmitted over the office trunks, being superimposed on the ringing circuit of the called station, and means at the called station for receiving the impulses and transposing them into visible numerals, whereby the telephone number of the calling station is recorded.
- 25 17. The combination with an automatic telephone system wherein calling and called stations are connected through central office equipment

of a recording system including, means associated with the calling station and actuated when the connection between stations is made for setting up electrical impulses which represent the telephone number of the calling station, said means being so connected to the central office equipment through the calling station that the electrical impulses are transmitted over the office trunks, being superimposed on the ringing circuit of the called station, means at the called station for receiving the impulses and transposing them into visible numerals, whereby the telephone number of the calling station is recorded, and means for clearing said recording when the telephone instrument of the called station is subsequently used.

30 18. The method of transmitting the telephone number of a calling station to a called station which includes, setting up electrical impulses which represent the number of the calling station immediately after the ringing circuit to the called station is complete, transmitting said impulses over said ringing circuit to the called station, receiving said impulses at the called station, and transposing the same into visible indications to indicate at the called station the number of the calling station.

35 19. The method of transmitting the telephone number of a calling station to a called station which includes, automatically setting up electrical impulses which represent the number of the calling station as soon as the ringing circuit to the called station is complete, transmitting said impulses to the called station, receiving said impulses at said called station, and transposing said impulses into visible indications to indicate the number of the calling station at said called station.

40 20. The method of transmitting the telephone number of a calling station to a called station which includes, automatically setting up electrical impulses which represent the number of the calling station as soon as the ringing circuit to the called station is complete, transmitting said impulses to the called station over said ringing circuit and during the first ringing period, receiving said impulses at said called station, and transposing said impulses into visible indications to indicate the number of the calling station at said called station.

45 21. The method of transmitting the telephone number of a calling station to a called station which includes, automatically setting up electrical impulses which represent the number of the calling station as soon as the ringing circuit to the called station is complete, transmitting said impulses to the called station over said ringing circuit and during the first ringing period, receiving said impulses at said called station, transposing said impulses into visible indications to indicate the number of the calling station at said called station, and clearing the visible indications when the telephone instrument at the called station is used to make a subsequent call.

50 22. The method of transmitting the telephone number of a calling station to a called station which includes, automatically setting up electrical impulses which represent the number of the calling station as soon as the ringing circuit to the called station is complete, transmitting said impulses to the called station, receiving said impulses at said called station, transposing said impulses into visible indications to indicate the number of the calling station at said called station, and automatically destroying the visible in-

dications upon the subsequent use of the telephone instrument at the called station.

23. The method of transmitting the telephone number of a calling station to a called station which includes, automatically setting up electrical impulses which represent the number of the calling station, transmitting said impulses to the called station, receiving said impulses at the called station, transposing said impulses into visible indications to indicate the number of the calling station at the called station, and automatically clearing the indications to destroy the same upon the next subsequent use of the telephone instrument at the called station.

15 24. The method of transmitting the telephone number of a calling station which includes, setting up at the calling station electrical impulses representing the number of such calling station as soon as the ringing circuit to the called station is complete, such impulses being of a different frequency than the frequency of the ringing current so as not to interfere therewith, transmitting said impulses to the called station during the ringing period, and receiving and transposing said impulses into visible indications at the called station to indicate the number of the calling station.

25 25. A telephone system for transmitting the telephone number of a calling station to a called station including, means for setting up electrical impulses which represent the number of the calling station and being automatically operated when the ringing circuit to the called station is complete, means for transmitting said impulses to the called station, means at the called station for receiving said impulses, and registering means at the called station actuated by the receiving means for transposing the electrical impulses into visible indications to record the telephone number of the calling station.

40 26. A telephone system for transmitting the telephone number of a calling station to a called station including, means for setting up electrical impulses which represent the number of the calling station and being automatically operated when the ringing circuit to the called station is complete, means for transmitting said impulses to the called station, means at the called station for receiving said impulses, registering means at the called station actuated by the receiving means for transposing the electrical impulses into visible indications to record the telephone number of the calling station, and means for clearing said registering means to destroy the indication when the telephone instrument at the called station is subsequently used.

55 27. A telephone system for transmitting the telephone number of a calling station to a called station including, means for setting up electrical impulses which represent the number of the calling station and being automatically operated when the ringing circuit to the called station is complete, means for transmitting said impulses to the called station and over the ringing circuit during the initial ringing period, means at the called station for receiving said impulses, and registering means at the called station actuated by the receiving means for transposing the electrical impulses into visible indications to record the telephone number of the calling station.

70 28. A telephone system for transmitting the telephone number of a calling station to a called station including, means for setting up electrical impulses which represent the number of the call-

ing station and being automatically operated when the ringing circuit to the called station is complete, means for transmitting said impulses to the called station and over the ringing circuit during the initial ringing period, means at the 5 called station for receiving said impulses, registering means at the called station actuated by the receiving means for transposing the electrical impulses into visible indications to record the telephone number of the calling station, and 10 means actuated by the receiver hook of the telephone instrument at the called station for clearing the registering means upon the next subsequent use of said instrument.

15 29. A telephone recording system for transmitting and recording the number of a calling station to a called station including, means independent of the telephone instrument at the calling station for setting up electrical impulses which represent the number of the calling station, such impulses being of a frequency different from the normal ringing current of the telephone system, transmitting said impulses to the called station over the ringing circuit of the called station and during the ringing period, means at 20 the called station for receiving said impulses, and means for transposing the same into visible indications to indicate the number of the calling station at the called station.

25 30. A telephone recording system for transmitting and recording the number of a calling station to a called station including, means independent of the telephone instrument at the calling station for setting up electrical impulses which represent the number of the calling station, such impulses being of a frequency different from the normal ringing current of the telephone system, transmitting said impulses to the called station over the ringing circuit of the called station and during the ringing period, 40 means at the called station for receiving said impulses, means for transposing the same into visible indications to indicate the number of the calling station at the called station, and means actuated by the receiver hook of the telephone 45 instrument at the called station for clearing the indications upon the next subsequent use of said instrument.

35 31. The combination with an automatic telephone system wherein calling and called stations 50 are connected through central office equipment of a recording system including, means at the calling station independent of the telephone instrument at such calling station for setting up electrical impulses which represent the telephone 55 number of said calling station, said impulses being of a higher frequency than the normal ringing current of the telephone system, means for superimposing said high frequency impulses on the ringing circuit of the called station, and 60 means at the called station for receiving said impulses and transposing them into visible numerals, whereby the telephone number of the calling station is recorded at the called station.

65 32. The combination with an automatic telephone system wherein calling and called stations are connected through central office equipment of a recording system including, means at the calling station independent of the telephone instrument at such calling station for setting up 70 electrical impulses which represent the telephone number of said calling station, said impulses being of a higher frequency than the normal ringing current of the telephone system, means for 75

superimposing said high frequency impulses on the ringing circuit of the called station, means at the called station for receiving said impulses and transposing them into visible numbers, whereby the telephone number of the calling station is recorded at the called station, and means

actuated by the receiver hook of the telephone instrument at the called station for automatically clearing said indications upon the next subsequent use of said instrument.

KENNETH R. HYMAN.
